UNITED STATES PATENT OFFICE.

HARRISON J. L. FRANK, OF DETROIT, MICHIGAN, ASSIGNOR TO MUTUAL ELECTRIC AND MACHINE COMPANY, OF DETROIT, MICHIGAN, A CORPORATION OF WEST VIRGINIA.

THEATER SWITCHBOARD.

Application filed October 26, 1921. Serial No. 510,597.

To all whom it may concern:

Be it known that I, HARRISON J. L. FRANK, a citizen of the United States, and residing at Detroit, in the county of Wayne and State of Michigan, have invented a new and Improved Theater Switchboard, of which the following is a specification.

This invention relates to switch boards which are employed to control the lighting 10 of the stages of theaters and other spaces where the lights are changed at intervals in a predetermined manner to affect the illumination of the scenery and the persons occupying such spaces, and its object is to 15 provide a series of switch operating devices which can be so adjusted and so connected in advance without affecting the illumination already in use that the complete operation of a single lever will bring into action any 20 desired inoperative lights and put out of action any of the lights in operation before the desired change which are not to be used after the change, and to leave unaffected such lights as are to so remain in use.

25 This invention consists of a series of switches in a group and a control lever for the group adapted to be moved forward and backward, an operating handle for each switch adapted to move forward and backward 30 to operate the switch, means connected to the control lever and to the operating handles, and means on the operating handles adapted to be positioned so as to operatively engage the connecting means actuated by the 35 control lever on either the forward or backward movements of the control lever, or both said movements or neither of them, as may be desired, so that the operating handles will move with the control lever or remain 40 stationary as may be desired.

The invention also consists in means operatively connecting the control levers and a master lever for simultaneously actuating the control levers.

45 It further consists in the details of construction illustrated in the accompanying drawings and particularly pointed out in the claims.

In the drawings, Fig. 1 is a front elevation 50 of a switch board embodying the present invention. Fig. 2 is an elevation of a pair of switches mounted on the back of the switch board. Fig. 3 is a front elevation of a switch operating handle. Fig. 4 is a

side elevation thereof. Fig. 5 is a section 55 on the line 5—5 of Fig. 3. Figs. 6, 7 and 8 are sections on the line 6—6 of Fig. 3, showing the parts in three different positions. Fig. 9 is a side elevation of a switch. Fig. 10 is a side elevation of a control lever. 60 Similar reference characters refer to like parts throughout the several views.

The switch board 1 shown in the drawings is of usual form and on its rear side are any desired number of switches of any desired type, adapted to be opened and closed by operating handles. In Figs. 2 and 9 I have illustrated a switch which is adapted for the present purpose and consists of a bracket 3 attached to the board and carrying a pin 4 for a lever 5. A link 6 extends through an opening 7 in the board between the operating handle and the pin 8 in the lower arm of the lever. A block 10 of insulating material is attached to the arm 11 of the lever and carries terminals 12 for the fuses 13. Blades 14 extend from the terminals 12 over the edges of the block 10 and are adapted to engage the spring terminals 15 and 16 mounted on the board 1. Conductors of any desired type may connect these terminals 15 and 16 to the current source and to the lights served by the switch. In Fig. 2 I have shown flat strips 17 connecting to the terminal 15, while in Fig. 9 I have shown the conductor ends 18. A stop 19 may be attached to the board 1 to engage a small plate 20 on the block 10 to limit its inward movement.

The advantage of this switch lies in the 90 fact that when open and swung out, the fuses and all other exposed parts have no current so that a person passing the board is in no danger of injury from current in those parts which project from the board.

95 Mounted on the board 1 are any desired number of shafts 22 supported by the bearings 23, and a control lever 24 is connected to each shaft. Mounted on the shaft are a number of operating arms 25 each having 100 two perforated lugs 26 and 27 in which the handle pin 28 is vertically slidable. The link 6 which connects to the switch is pivoted on the pin 29 mounted on this arm 25. Adjacent each operating handle is a collar 30, 105 attached to the shaft 22 in any desired manner, a set screw 32 being shown, and this collar may be provided with hard bearing

strips 33. A notch 34 is formed in this collar to receive the lower end of the pin 28 and this collar is also provided with two cushions 35 adapted to engage the stop bar 5 36 which extends along near the board 1 between the bearings 23. A spring 37 may be attached to the shoulder 38 on this collar and is adapted to frictionally engage this bar 36 as indicated in dotted lines in Fig. 8, 10 when the operating handle is swung out to switch-closing position. These collars always move with the shaft and tubular spaces 39 may be mounted on the shaft to prevent endwise movement of the operating handles. 15 On the handle pin 28 is a washer 41 resting on a pin 42 and the spring 43 presses down on this washer and pin 42. On the pin 28 above the lug 26 is a collar 44 having a slot 45 through which the positioning pin 46 20 extends at right angles to the handle pin 28. A spring 47 attached to the end of the arm 25 is adapted to enter the notches 48 in the upper end of this collar 44. See Fig. 5. A handle 49 is on the upper end of the handle 25 pin and the lower end of this pin is beveled as shown in Fig. 8.

The lug 26 is preferably marked with the words Off, Pos., On and Ind. to indicate that when the positioning pin is over the word 30 Off, which brings the handle pin to the position shown in Fig. 4 against a stop 50, rotation of the shaft by the control lever and the collar 30 in the direction indicated by the arrow in Fig. 4 will cause the shoulder 51 35 on the collar to engage the handle pin 28 and the operating lever to swing out and pull out the link 6 and thereby open the switch connected thereto. On the reverse movement of the control lever the shoulder 52 of this 40 collar engages the beveled face 53 of the lower end of the handle pin and lifts it without swinging it. All further reciprocations of the collar 30 will have no effect on this operating handle which remains swung 45 out. If then a light or group of lights controlled by that particular operating handle is to be cut out at the next change of lights, the pin 46 is positioned at Off.

When the lights controlled by any switch 50 are to be left on or active, the pin 46 of that particular operating handle is swung to On position, as indicated in Fig. 7. Any outward movement of the collar 30 will cause its shoulder 51 to lift the pin 28 through engagement with the inclined face 53 of the end of the pin, but the operating handle will not move. Should the handle have been swung out, its pin will drop into the notch 34 of the adjacent collar just as soon as the collar 55 has been swung out, the return movement of the lever 24 and the shaft 22 serving to carry this handle to switch-closing position when the lights are changed. All 60 handles in the On position always either 65 move to or remain in switch-closing position.

When the pin 46 is moved to Pos. position, which is half way between On and Off, the end of the pin 28 is so located (as shown in Fig. 6) that neither shoulder 51 or 52 has any engagement with the inclined surface 53. The result is that the operating handle moves with the control lever and the lights controlled thereby go on or off as the control lever is swung toward or from the board 1.

I have shown a cam 54 formed on the upper end of the arm 25 and a ledge 55 at the upper end thereof, on which the pin 46 is adapted to rest and hold the handle pin 28 entirely out of the notch 34. This independent or Ind. position permits this operating handle to be moved at will without affecting or being affected by the other handles or levers.

It will be noticed that the beveled face 53 is in two planes meeting at an angle of about 120 degrees. See Figs. 6 and 8. This results from the stops 48 for Off and On being 120 degrees apart. The lug 26 is preferably formed with a groove 56 at the Pos. stop in order to permit a slightly greater 90 downward movement of the handle pin, as shown in Fig. 6. The collar 44 does not move up or down but the pin 46 is vertically movable in the slot 45. An oil hole is indicated at 57. The handles 49 may be used to move the pins 46 around if desired, and any one of the operating handles positively connected to a shaft 22, as indicated in Fig. 6, may be used to operate that shaft and the handles thereon. A tell-tale light 58 for each switch 100 and handle may be mounted just above the handle and a card 59 for the names of the lights may be attached to the board adjacent thereto.

A master lever 61 may be mounted on a short shaft 62 carried by bearings 63 on the board 1 and a crank 64 on this shaft may have a bolt 65 connecting to a bar 66. On each shaft 22 is an additional collar 67, an operating arm 68, and a handle 169 of the same construction as shown in Figs. 3 to 8, connected to a pin which again engages in a notch in the collar 67 or is entirely free therefrom as may be desired. The bar 66 is attached to each operating arm 68 by a bolt 69 and the actuation of the master lever 61 will then result in actuations or positioning of any of the groups of the several switches on the board in the manner predetermined by the control pins 46 on the several operating arms 25 and 68.

I have also shown a main switch lever 71 in Figs. 1 and 10 carrying a pin 72 which engages the link 73 leading to the master switch. The lever is mounted on a pin 74 carried by a bracket 75. The lever may be secured in the "in" or "out" position by the lock 76 extending through the holes 77 or 78 in the bracket and in the lower arm of the lever.

The details of construction and arrangement of the parts may all be changed by those skilled in the art without departing from the spirit of my invention as set forth in the following claims.

Thus, the equivalent of the pins 28 might be mounted in the collars 30 and sockets mounted on the arms 25 to receive these pins, the pins being rotatable as above described or the socket formed with the proper inclined shoulders which may be positioned by an arm 46.

Attention is called to the form of the detents 37 at the free ends of the springs 37 which are attached to the parts 38 of the control arms 25. I prefer the bar 36 to be in the form of a channel with its flanges extending toward the switch-board so that when the spring is swung up as indicated in dotted lines in Fig. 8, the detent will engage over the lower flange of the channel bar. The advantage of this channel is that the detent has a better grip and thus holds the switch open. The sum of the resistances of all these springs is considerable so that when the operator begins to push a control lever 24 toward the switch-board to close the predetermined switches, this resistance will require him to exert considerable force. But when this resistance is overcome and suddenly ceases, the force applied to the lever continues and the lever 24 is moved to switch-closing position at great speed, which is very desirable in order to reduce arcing at the switch contacts as much as possible.

In addition thereto this momentum of the switches and of the operator conduces to complete closing of the switches. These springs also prevent undesired movements of the switches and their control arms due to the friction of the pins 28 on the collars 30 and hold these arms and switches in proper position to be connected to the operating shafts and control levers.

I claim:—

1. In a switch-board, a shaft, a lever to turn the shaft back and forth, a switch operating arm rotatable on the shaft, a pin slidably mounted in said arm, a spring to press the pin toward the shaft, a collar attached to the shaft and having a notch to receive one end of the pin, said end of the pin having an inclined face which, when engaged by a wall of the notch, will cause the pin to be lifted to permit the shaft to turn independently of said switch-operating arm.

2. In a switch-board, a shaft, a lever to turn the shaft back and forth, a switch operating arm rotatable on the shaft, a pin slidably mounted in said arm and having an inclined face, a spring to press the pin toward the shaft, a collar attached to the shaft and having a notch to receive one end of

the pin, and means to turn the pin to present said inclined face to the front or back wall of the notch or position it transversely to said walls.

3. In a switch-board, a controlling member, means to move it back and forth, a series of switch-operating devices, a manually operable positioning device for each operating device, means to hold each of said positioning devices in any one of four positions, and a connector for each switch-operating device adapted to be positioned by the manually operable device to cause said switch-operating device to move with the controlling member during one or the other or both of the movements thereof, or to be entirely disengaged therefrom.

4. In a switch-board, a controlling shaft, a lever to turn it back and forth through limited arcs, a series of switch-operating devices mounted on the shaft, a manually operable positioning device for each switch-operating device, means to hold each positioning device in any one of four positions, and a pin mounted on each switch-operating device adapted to be positioned by the manually operable device to cause said switch-operating device to move with the shaft during one or the other or both of the movements of said shaft or to be entirely unaffected thereby.

5. In a switch, a shaft, a lever to turn the shaft back and forth, a switch-operating arm rotatable on the shaft, a pin slidably mounted in said arm, a spring to press the pin toward the shaft, a handle on the outer end of the pin, and a collar attached to the shaft and having a notch to receive one end of the pin, said end of the pin having an inclined face which, when engaged by a wall of the notch, will cause the pin to be lifted to permit the shaft to turn independently of said switch-operating arm.

6. In a switch, a shaft, a lever to turn the shaft back and forth, a switch-operating arm rotatable on the shaft, a pin slidably mounted in said arm, a spring to press the pin toward the shaft, a handle on the outer end of the pin, a collar attached to the shaft and having a notch to receive one end of the pin, said end of the pin having an inclined face which, when engaged by a wall of the notch, will cause the pin to be lifted to permit the shaft to turn independently of said switch-operating arm, and a spring mounted on the switch-operating arm to hold the pin to present the inclined face thereon to the desired wall of said notch.

7. In a switch-board, a plurality of shafts and bearings therefor, a lever to turn each shaft back and forth, a group of switch-operating arms on each shaft, means to cause each arm to move with its shaft during one or the other or both of the movements of the shaft if desired, a master lever

adapted to move forward and backward, an additional control arm on each shaft, means connecting the master lever to each control arm, and means to connect each control arm 5 to its shaft to move the shaft with the master lever during one or the other or both of its movements if desired.

8. The combination of a plurality of members each adapted to be moved in two 10 directions and a connecting device between them susceptible of a plurality of operative positions, one of said positions permitting independent operations of the members and another of said positions compelling said 15 members to move together in both directions.

9. The combination of an operating member and an operated member, and a connecting device between them susceptible of a 20 series of positions, one of said positions permitting independent operations of the two members, a second position compelling both members to act together, and a third position compelling the members to act together 25 when the operating member moves in one direction and permitting the operating member to move in the opposite direction without affecting the operated member, said 30 operations being predetermined by the positioning of the connecting device in advance of said operations.

10. The combination of operating and operated members and a connecting device between them adapted to be given a series 35 of positions, one of said positions permitting independent operation of the two members and two other positions compelling the members to act together when the operating member moves in either one or the other direction respectively but without affecting the operated member when the operating member moves in the opposite direction, said 40 operations being predetermined by the positioning of the connecting device in advance of said movements.

11. The combination of operating and operated members and a connecting device between them adapted to be given a series of 50 positions, one of said positions compelling both members to move together and two other positions compelling the operated member to move with the operating member when that moves in either one direction or the other respectively but without affecting the operated member when the operating member moves in the opposite direction in either case, said operations being predetermined by the positioning of the connecting device in advance of said movements.

12. The combination of a control lever and a switch, and a connecting device between them adapted to be given a series of positions, one of said positions permitting the switch to be operated independently of 60 the control lever, a second position causing

the switch to be opened and closed with the forward and backward movements of the control lever, a third position causing the switch to be opened with one movement of the control lever and remain open during 70 all subsequent movements thereof, and a fourth position causing the switch to be closed with one movement of the control lever and remain closed during all subsequent movements of the control lever, said 75 operations being predetermined by the positioning of the connecting device in advance of said movements of the control lever.

13. The combination of a control lever 80 and a switch, and a connecting device between them adapted to be given a series of positions, one of said positions permitting the switch to be operated independently of the control lever, a second position causing 85 the switch to be opened and closed with the forward and backward movements of the control lever, and a third position causing the switch to be opened with one movement of the control lever and remain open during 90 all subsequent movements of the control lever, said operations being predetermined by the positioning of the connecting device in advance of said movements of the control lever.

14. The combination of a control lever and a switch and a connecting device between them adapted to be given a series of positions, one of said positions causing the switch to be opened and closed with the forward and backward movements of the control lever, a second position causing the switch to be opened with one movement of the control lever and remain open during 105 all subsequent movements thereof, and a third position causing the switch to be closed with one movement of the control lever and remain closed during all subsequent movements of the control lever, said operations being predetermined by the positioning of the connecting device in advance of said movements of the control lever.

15. The combination of a control lever and a switch and a connecting device between them adapted to be given a series of positions, one of said positions permitting the switch to be operated independently of the control lever, a second position causing the switch to be opened and closed with the forward and backward movements of the control lever, and a third position causing the switch to be closed with one movement of the control lever and remain closed during 120 all subsequent movements of the control lever, said operations being predetermined by the positioning of the connecting device in advance of the said movements of the control lever.

16. The combination of a control lever 125

- and a switch and a connecting device between them adapted to be given a series of positions, one of said positions permitting the switch to be operated independently of the control lever, a second position causing the switch to be opened with one movement of the control lever and remain so during all subsequent movements thereof, and a third position causing the switch to be closed with one movement of the control lever and remain closed during all subsequent movements of the control lever, said operations being predetermined by the positioning of the connecting devices in advance of said movements of the control lever.
17. In a switch-board, a shaft, a lever to turn the shaft back and forth, a switch operating arm rotatable on the shaft, a pin slidably mounted in said arm, a spring to press the pin toward the shaft, a collar attached to the shaft and having a notch to receive one end of the pin, means to withdraw the pin from said notch, a stationary bar adjacent said shaft to limit the movements of said arm, and a resilient member mounted on said arm and adapted to engage said bar when the arm has been moved to the limit of one of its movements.
18. In a switch-board, a shaft, means to turn the shaft back and forth, a switch operating arm rotatable on the shaft, a collar attached to the shaft, resilient means to connect said arm to said collar, means to disconnect the arm and collar, a stationary bar adjacent said shaft to limit the movements of said arm, and a resilient member mounted on said arm and adapted to engage the bar to hold said arm at the end of one of its movements.
19. In a switch-board, a shaft, a lever to turn the shaft back and forth, a switch operating arm rotatable on the shaft, a pin slidably mounted in said arm, a spring to press the pin toward the shaft, a collar attached to the shaft and having a notch to receive one end of the pin, means to withdraw the pin from said notch, a stationary, independently-mounted stop member to limit the movements of the switch-operating arm, and resilient means connecting the switch-operating arm and the stop member to hold them together.
20. In a switch-board, a shaft, means to turn the shaft back and forth, a switch-operating member mounted on the shaft, means to connect and disconnect the switch-operating member and shaft, a stationary, independently-mounted stop member to limit the movements of the switch-operating member, and means connecting the switch-operating member and the stop member to hold them together.
21. The combination of operating and operated members and a connecting device between them adapted to be given a series of positions, one of said positions compelling both members to move together and two other positions compelling the operated member to move with the operating member when that moves in either one direction or the other respectively but without affecting the operated member when the operating member moves in the opposite direction in either case, said operations being predetermined by the positioning of the connecting device in advance of said movements, and a switch for each of said operated members comprising stationary contacts, conductors connected thereto, a movable support, insulated contacts mounted thereon and fuses connecting the insulated contacts, said movable contact and fuses being electrically disconnected from the conductors when the switch is open.
22. The combination of a control lever and a switch, a connecting device between them adapted to be given a series of positions, one of said positions permitting the switch to be operated independently of the control lever, a second position causing the switch to be opened and closed with the forward and backward movements of the control lever, a third position causing the switch to be opened with one movement of the control lever and remain open during all subsequent movements thereof and a fourth position causing the switch to be closed with one movement of the control lever and remain closed during all subsequent movements of the control lever, said operations being predetermined by the positioning of the connecting device in advance of said movements of the control lever, and a switch for each of said operated members comprising stationary contacts, conductors connected thereto, a movable support, insulated contacts mounted thereon and fuses connecting the insulated contacts, said movable contacts and fuses being electrically disconnected from the conductors when the switch is open.
23. In a switch board, an actuating device and means to move it backward and forward, and a switch operating device adjacent the actuating member and embodying means to connect it to the actuating member, said connecting means being adapted when in one position to cause the operating device to move backward and forward with the actuating device, and when in a second position to cause the operating device to move with the actuating device when that moves forward only, and when in a third position to cause the operating device to move with the actuating device when that moves backward only.
24. In a switch board, a switch and a switch operating device to open and close the switch, an actuating device therefor adapted to move backward and forward, a

connector adapted to have three positions, one in which it causes the switch operating device to move in both directions with the actuating device to open and close said switch, and two other positions in which it causes the switch operating device to move with the actuating device to alone open or close said switch, a spring to hold the connector in either of its three positions, and 10 manually operable means to position the connector.

25. In a switch board, a switch and a switch operating device to open and close

the switch, an actuating device therefor adapted to move backward and forward, a 15 connector adapted to have three positions, one in which it causes the switch operating device to move in both directions with the actuating device to open and close said switch, and two other positions in which it causes the switch operating device to move with the actuating device to alone open or close said switch, and manually operable means to position the connector.

HARRISON J. L. FRANK.
